UNITED STATES PATENT OFFICE.

WILLIM WOICESKI, OF BLOOMINGTON, ILLINOIS.

IMPROVEMENT IN PUNCHING-MACHINES.

Specification forming part of Letters Patent No. 142,317, dated August 26, 1873; application filed July 3, 1873.

To all whom it may concern:

Be it known that I, WILLIM WOICESKI, of Bloomington, in the county of McLean and in the State of Illinois, have invented certain new and useful Improvements in Machine for Punching Stove-Pipes, Boiler-Iron, &c.; and do hereby declare that the following is a full, clear, and exact description thereof, reference being had to the accompanying drawings and to the letters of reference marked thereon, making a part of this specification.

The nature of my invention consists in the construction and arrangement of a machine for punching stove-pipes, boiler-iron, &c., as will be hereinafter more fully set forth.

In order to enable others skilled in the art to which my invention appertains to make and use the same, I will now proceed to describe its construction and operation, referring to the annexed drawing, in which—

Figure 1 is a front view, and Fig. 2 a side elevation, of my machine.

A represents a stand or table of any suitable dimensions, upon which are secured two cast-metal frames, B and C. In the upper end of the frame B is a horizontal shaft, *a*, with crank *b* at one end, from which a pitman, D, connects with a treadle, E, under the table, for operating the machine.

The machine may be operated by steam or water power by connecting such power by a belt with a pulley, *d*, on the shaft *a*. Upon this shaft is also a large cog-wheel, G, which gears with a pinion, *e*, on a shaft, *a'*, below and parallel with the shaft *a*, and this shaft *a'* carries the fly-wheel H.

On the shaft *a* within the frame B is secured a pinion, *f*, which gears with a large cog-wheel, I, made fast on a horizontal shaft, *a''*, in the upper end of the frame C. On one end

of this shaft is a crank-pin, *i*, upon which is placed a short pitman, J. The lower end of this pitman is forked, and in the same is pivoted a plunger or slide, K, having a punch formed on or attached to its lower end. The plunger or slide K moves in a suitable box or guide, L, which is either formed on or attached to the frame C.

By working the treadle, or by applying any other suitable power, the plunger is operated up and down, causing the punch to make holes through the material placed in position for that purpose.

For heavy work an anvil, M, is placed on the stand A, directly under the punch; while for light work an L-shaped post, N, is used, said post being secured on the stand and capable of being swung in and out to or from under the punch. The anvil M is to be removed when the post N is to be used. The stove-pipe is passed over the horizontal arm of the L-shaped post N, which is then swung around under the punch, when the punch descends and makes the hole.

Having thus fully described my invention, what I claim as new, and desire to secure by Letters Patent, is—

In combination with a punching mechanism operated by gearing, substantially as described, the revolving L-shaped post N, over which the pipe is placed and swung in under the punch, as set forth.

In testimony that I claim the foregoing I have hereunto set my hand this 24th day of May, 1873.

WILLIM WOICESKI.
